UNITED STATES PATENT OFFICE.

WALTER B. SCHREYER, OF DETROIT, MICHIGAN.

DETACHABLE LINK.

1,252,184.

Specification of Letters Patent.

Patented Jan. 1, 1918.

Application filed December 13, 1915, Serial No. 66,530. Renewed September 22, 1917. Serial No. 192,830.

To all whom it may concern:

Be it known that I, WALTER B. SCHREYER, (whose post-office address is 90 Perry street,) a citizen of the United States, residing at 5 Detroit, in the county of Wayne and State of Michigan, have invented certain new and useful Improvements in Detachable Links; and I do hereby declare the following to be a full, clear, and exact description of the 10 invention, such as will enable others skilled in the art to which it appertains to make and use the same.

The invention relates to improvements in detachable links, or the like, and more particularly to that type of such links, commonly termed as "lap-links," and which are adapted for use as a coupling element between adjacent chain ends, or other similar devices it is desired to connect.

20 An object of the invention is to provide a construction of this character, in which the contour of the same, when in closed or operative position, is continuous and uninterrupted, by indentations or protuberances or 25 the like, and one which is adapted for easy and rapid application for the purpose mentioned.

With this and other objects in view, the invention resides in the certain new and 30 novel construction, which is to be herein-after more fully described, set forth in the appended claims, and illustrated in the accompanying drawing, in which,

Figure 1 is a top plan view of the preferred embodiment of the invention,

Fig. 2 is a top plan of the same in open position,

Fig. 3 is a side elevation, and

Fig. 4 is a vertical longitudinal section on 40 the line 4—4 of Fig. 1.

Reference being had to the accompanying drawing, in which similar characters of reference designate corresponding parts in the several views thereof, the invention comprises a pair of superposed link elements 45 —10— and —11—, each formed to provide oppositely disposed, substantially J-shaped, hook elements —12—, the members —13—, of which, being connected in spaced, longitudinally offset, parallel relation, by means of a pivot-plate —14—, the free ends —15—, of the members —13—, projecting beyond the edges of the pivot-plate —14— and in opposite directions therefrom, being beveled, 55 as at —16—, while the free ends —17—, of the hook elements —12—, terminate in a plane

with the free ends —15—, of the members —13—, and are also beveled, as at —18—.

On the opposed faces of the link elements —10— and —11—, at points thereon directly 60 opposite the openings between the ends —15— and —17—, of the members —13— and the hook elements —12—, respectively, and obliquely thereof with respect to one another, and rising therefrom, are abutments —19—, each having its opposite end walls beveled, as at —20—, to correspond to the bevels —16— and —18—, of the said adjacent ends —15— and —17—.

The link elements —10— and —11— are, 70 when properly superposed, pivotally movable with respect to each other on a pivot pin —21—, which is passed through alining openings formed in the pivot-plates —14—, and secured therein in any desired manner. 75

From the foregoing, it will be readily apparent that the invention provides for an inexpensive, compact and efficient device of the character mentioned, the construction of which admits of the contours of the opposed 80 faces of the link elements contacting throughout the area thereof, whereby to distribute the strain, to which the device may be subjected equally to both of the elements, the beveled contacting surfaces tending to reduce the strain brought to bear on the pivot pin, and one in which the outer contour of the assembled elements is continuous and uninterrupted, such as is not usual with the ordinary or similar type of such device. 85 90

Having thus fully described the invention, what is claimed, is:—

1. A device of the character described comprising a pair of superposed link elements pivotally supported at their centers, 95 each being formed to provide a pair of oppositely disposed J-shaped hook members integrally connected intermediate their ends by a transverse plate.

2. A device of the character described 100 comprising a pair of substantially oval shaped link elements, each being formed to provide a pair of oppositely disposed hook members integral with a transverse plate, and an inset pin pivotally connecting 105 said plates.

3. A device of the character described comprising a pair of elongated link-elements, each having openings disposed at opposite sides of the longitudinal center thereof, and obliquely with respect to each other, alining 110 transverse bars centrally disposed of

- each link-element, a pivot pin connecting said transverse bars, and abutments carried by each link-element and adapted to be engaged by the walls of said openings.
- 5 4. A device of the character described comprising a pair of elongated link-elements each formed to provide oppositely disposed J-shaped members having bevel walled openings disposed at opposite sides 10 of the longitudinal center thereof, and obliquely with respect to each other, centrally disposed alining transverse bars con-

necting the J-shaped members, a pivot pin connecting said transverse bars, and abutments, having their opposite ends beveled, 15 carried by each link-element and adapted to be engaged by the beveled walls of said openings.

In testimony whereof I affix my signature, in presence of a witness.

WALTER B. SCHREYER.

Witness:

DAVID W. REINHOLD.
